[57] CLAIM

The ornamental design for a telephone key arrangement, as
shown and described.

DESCRIPTION

FIG. 1 is a perspective view of a telephone key arrangement
showing our new design; and,
FIG. 2 is a front elevational view thereof.

The non-disclosed portions of the button edges are the same
in appearance as the edges disclosed in FIG. 1.
The broken line showings of FIGS. 1 and 2 are for illustrative
purposes only and form no part of the claimed design.
